UNITED STATES PATENT OFFICE

FRANK C. FROLANDER, OF ELIZABETH, NEW JERSEY, ASSIGNOR TO MERGENTHALER LINOTYPE COMPANY, A CORPORATION OF NEW YORK

PRINTING UNIT

Application filed October 21, 1930. Serial No. 490,141.

This invention is directed to an improved printing unit which, while capable of more general application, is particularly suitable for telephone directories and similar classes 5 of publications. In revising the current editions of such publications to bring them up to date for subsequent issues, it is the usual practice to employ auxiliary printing systems, the most common of which includes 10 curved sheet metal form-plates and special type bars bearing impressions of the names and numbers to be listed. The type bars are in the form of thin metal strips with bent-over edges and, being relatively light in 15 weight, may be readily attached and detached to and from the form-plates, as desired. When a new name is to be entered on a page or an old number changed, the corresponding 20 impressions are first produced in a blank strip or bar by means of a special machine (which is also included in the equipment) and the bar is then inserted in its proper place in the form. After these operations 25 have been effected, the form is placed upon the drum of a small printing press (especially provided for the purpose) and a proof sheet showing the revisions is thus obtained and sent to the telephone operator for reference. As the time approaches for a new 30 edition, the proof sheets are collected and all of the matter in its final or revised form is set up and cast in linotype machines, the slugs being thereafter locked up in the usual galleys and sent to the press for printing. With this 35 old prevailing system, the installation not only involves a considerable initial outlay, but in addition it is costly to maintain.

The present invention is intended to simplify the foregoing procedure and contemplates certain improvements whereby the 40 page forms, as produced on a linotype machine, may be used for the original printing of the publications as well as for the subsequent revisional work required in putting out 45 later editions. To this end, the slugs or linotypes employed are cast of substantially less than normal type height so that the printing forms will be of a minimum weight, and a special galley is provided with means for anchoring the individual slugs against escape 50

to permit handling of the forms with the desired degree of safety.

In the preferred embodiment illustrated, the slugs are formed with half-round notches in their opposite ends, and the galley is divided by a plurality of fixed parallel partition plates into separate compartments wherein the slugs are stacked in columns. The notches in the slugs are adapted to fit over correspondingly shaped beads or ribs 55 formed on the partitions and the side walls of the galley, so that while the slugs are normally anchored against vertical displacement they may be separated facewise from one another for quick removal and replacement. The galleys are flat and of rectangular form, as usual, and ordinarily will be no larger than the individual pages; hence, a close arrangement of the forms in storage 60 racks is permitted and a minimum storage 65 space for the racks required. When ready for the press, the galleys with the contained forms are clamped in a chase, which is adapted to support them at the proper level to bring the printing surfaces of the slugs at 70 the required type height.

The exact construction and arrangement of the parts will best be understood from the detailed description to follow.

In the accompanying drawings, the invention has been shown merely in preferred form and by way of example, but obviously many changes and variations may be made therein, which will still be comprised within 80 its spirit. It should be understood therefore, that the invention is not limited to any specific form or embodiment except in so far as such limitations are specified in the appended claims.

Referring to the drawings:

Fig. 1 is a perspective view of the improved galley, showing the means for holding the slugs therein and the manner in which an individual slug may be removed;

Fig. 2 is an enlarged vertical longitudinal section of the galley;

Fig. 3 is a vertical transverse section taken on the line 3—3 of Fig. 2;

Fig. 4 is a vertical section taken on the 100

line 4—4 of Fig. 7, showing the improved galley and form in elevation;

Figs. 5 and 6 are comparative perspective views, showing respectively the improved 5 slug and a standard slug or linotype of the same length;

Fig. 7 is a plan view of the improved galley clamped in the chase; and

Fig. 8 is an end elevation of the chase.

As best shown in Figs. 1, 2 and 3, the improved galley or tray A consists generally of a flat rectangular base or bottom plate A¹, two parallel end walls A² and A³, two parallel side walls A⁴ and A⁵, and intermediate longitudinal partition plates A⁶, the latter being parallel to the side walls A⁴ and A⁵ and spaced apart to divide the galley into several sections or compartments A⁷ wherein the slugs or type bars are stacked in columns. 15 The width of the individual compartments A⁷ corresponds to the length of the slugs so as to support them endwise and in proper transverse alignment. The side walls A⁴ and A⁵ (Fig. 3), as well as the partition plates A⁶, are seated at their lower ends in shallow retaining grooves a formed in the bottom plate A¹ and are secured to said plate by fillister screws a¹. Both of the side walls A⁴, A⁵ (as may be observed in Fig. 3) are 20 provided with thin outer facing strips A⁸, which serve to increase the thickness of the walls beyond their retaining grooves and render them flush with the outer edges of the base plate A¹. The end walls A² and A³ are 25 likewise flush with the top and bottom edges of the base plate A¹, but in this instance the retaining grooves are omitted, the said walls being properly secured to and supported upon the base plate by screws and dowel pins a². All four sides of the galley A are 30 thus made smooth and square to fit against the clamping surfaces of the chase when the galley is positioned in the press. 35

As illustrated herein, the galley is provided with three partition plates A⁶, which therefore divide it into four distinct compartments A⁷, but it will be understood that a greater or less number might be employed or, if desired, the partitions eliminated entirely. 40 In the latter event, of course, the galley would be of relatively narrow proportions and adapted to contain only one column of slugs. Each of the sections or compartments A⁷ (see Fig. 1) is supplied with a pair of quoins or wedges B of a common type, which may be quickly adjusted to lock or release the columns as desired. Spacing blocks B¹ of a predetermined width are 45 arranged between the quoins B and the lower ends of the respective columns to insure a tight lock-up, and when removed (as they can be) they permit the slugs to be shifted facewise toward and from the bottom wall A² for a purpose presently to appear. 50

The slugs X employed are exceptionally

low, being scarcely more than a quarter of an inch in height, so that the gross weight of the galley and slug columns will be such as to permit the whole form to be lifted or shifted about with ease. One of these slugs (full size) is shown in Fig. 5 and, as will be noted, is formed at its opposite ends with a pair of half-round notches x. A slug Y of normal type height, but otherwise identical with the slug X, is shown alongside the latter in Fig. 6, and by comparing the two, it will be seen that the slug X will necessarily, due to its reduced height, receive far less side support in the galley A, (whose height is determined thereby), than would the slug Y in a galley of the appropriate or standard height. Consequently, in carrying out the present invention, means are provided for positively anchoring the slugs X against vertical displacement in the compartments A⁷, so as to avoid the danger of spilling the slugs from the galley in handling. Such means (as best shown in Figs. 1 and 2) consist of ribs or beads A⁹ extending longitudinally along the opposite sides of the partition plates A⁶ and the inner faces of the side walls A⁴ and A⁵. These ribs are adapted to fit loosely within the notches x of the slugs X when the latter are stacked in columns in the galley compartments A⁷, but it is pointed out that such interlocking engagement does not interfere with the facewise movement of the slugs when the spacing blocks B¹ are removed or when they are locked up by the quoins B. 90

While the partition plates A⁶ are intended primarily to separate as well as to supply the means for anchoring the slug columns in the form, they are herein utilized to produce the vertical or division lines which separate the columns of printed matter, and for that reason (see Figs. 1, 3 and 7) they are formed on their upper edges with ruling surfaces a³ disposed at the printing level of the slugs X. The partition plates A⁶ (see Figs. 1 and 2) 105 stop short of the rear wall A³ of the form A and the space thus provided is used for slugs, which may be of greater length than the slugs X, to print the headings and other matter at 110 the tops of the pages. 115

The space normally occupied by the block B¹ in an individual compartment is sufficient to permit a slug X, if canted facewise at an angle to the column, to be inserted in or extracted from the compartment without being obstructed by the anchoring ribs A⁹. In other words, when it is desired to replace a slug in any selected compartment, irrespective of its position in the column, it is merely necessary to remove the corresponding block B¹ and slide the slugs in front of the one affected down against the quoins B (see Fig. 1). It is then a simple operation to engage or disengage, whichever the case may be, first one and then the other of the notches x 125 130

of the affected slug with or from the corresponding anchor ribs A⁹ preparatory to interchange. As a matter of fact, the insertion or removal of a slug may be instantly effected by a single operation.

The chase C for holding the galley A in the press is constructed along the lines of those now in use (see Figs. 4, 7 and 8), the side members C¹, C² and the end members C³, C⁴ thereof being secured together in assembled relation by interlocking joint C⁵ located at the four corners of the chase. The side member C² at the right (Fig. 7) is formed on its inner face with a series of beveled surfaces c, which coincide with corresponding surfaces c¹ of a multiple wedge member C⁶, the latter being arranged alongside the member C² and adjustable endwise to lock or clamp the galley A against the opposite side member C¹ of the chase. The adjustments of the wedge bar C⁶ are effected by a set screw c² mounted in the lower chase member C³ and engaging a lip c³ at one end of said bar. The chase C is further provided with a pair of clamping screws c⁴ also mounted in the lower member C³ and adapted through the medium of a bar C⁷ (whose width corresponds substantially to the height of the chase) to lock the galley A against endwise displacement.

Since the height of the gallery A is considerably less than that of the chase C, it is proposed to equip the chase with a rectangular filler plate or block D upon which the galley is supported, the thickness of said plate being such as to locate the printing surfaces of slugs X in the galley A at the normal type height or level,—see Fig. 4. In this figure, as well as in Fig. 7, the galley A is shown properly positioned in the chase C, but for the sake of clearness in the illustration, the thin wood strips or reglets ordinarily used between the walls of the galley and the clamping surfaces of the chase have been omitted. In practice, however, when the galley is clamped in the chase, these strips will serve to compensate for the slight difference required in the size of the filler plate D and the galley A to insure a gripping of the galley, rather than the plate, between the bar C⁷ and the side walls of the chase.

It will now be seen that the improved galley and slugs offer all the advantages of the special forms and equipment heretofore employed for producing the proofs or reference sheets required in the development work of the telephone directories before issue. Moreover, while serving in this new capacity, the galleys will always be in proper condition for the press and thus dispense with the final proof-reading, editing, etc., incurred under the present practice or procedure.

Having thus described my invention, what I claim is:

1. A galley adapted to be placed in a print-

ing press, said galley containing printing slugs of substantially less than standard type height and presenting means rigidly secured to and forming a permanent part of the galley and adapted to anchor the individual slugs against vertical displacement, in combination with a chase adapted to support the galley at the standard type-high level.

2. A galley adapted to be placed in a printing press, said galley containing printing slugs of substantially less than standard type height and presenting means rigidly secured to and forming a permanent part of the galley and adapted to anchor the individual slugs against vertical displacement, in combination with a chase for clamping the galley in a press, and means associated with the chase for supporting the galley at the standard type-high level.

3. A galley adapted to be placed in a printing press, said galley containing printing slugs of substantially less than standard type height and presenting side and end walls as well as one or more partitions rigidly secured to and forming a permanent part of the galley and arranged parallel to the side walls and spaced apart to divide the galley into separate sections or compartments, and longitudinally extending ribs formed on the said partitions and side walls for anchoring the individual slugs against vertical displacement, in combination with a chase for clamping the galley in a press, and means associated with the chase for supporting the galley at the standard type-high level.

4. A galley adapted to be placed in a printing press, said galley containing printing slugs of substantially less than standard type height and comprising a bottom plate and side and end walls rising therefrom as well as one or more partitions rigidly secured to the bottom plate and arranged parallel to the side walls and spaced apart to divide the galley into separate sections or compartments, the side walls and partitions having longitudinal ribs or beads formed on their opposed faces and adapted to engage in recesses cast in the opposite ends of the slugs.

5. A galley adapted to be placed in a printing press, said galley containing printing slugs of substantially less than standard type height and comprising a bottom plate and side and end walls rising therefrom as well as one or more partitions rigidly secured to the bottom plate and arranged parallel to the side walls and spaced apart to divide the galley into separate sections or compartments, the side walls and partitions having longitudinal ribs or beads formed on their opposed faces and adapted to engage in recesses cast in the opposite ends of the slugs to anchor the slugs against vertical displacement, said ribs or beads being adapted to permit facewise movement of the slugs for insertion or removal.

6. A galley adapted to be placed in a printing press, said galley containing printing slugs of substantially less than standard type height and comprising a bottom plate and side and end walls rising therefrom as well as one or more partitions rigidly secured to the bottom plate and arranged parallel to the side walls and spaced apart to divide the galley into separate sections or compartments, the side walls and partitions having longitudinal ribs or beads formed on their opposed faces and adapted to engage in recesses cast in the opposite ends of the slugs to anchor the slugs against vertical displacement, said ribs or beads being adapted to permit facewise movement of the slugs for insertion or removal, and said partitions being provided on their upper edges with printing surfaces or rules extending longitudinally thereof.
7. A galley for printing slugs comprising a bottom plate and side and end walls rising therefrom, the bottom plate being formed with grooves adjacent to and parallel with the side walls, and partitions positioned in the grooves and affixed therein to the bottom plate and formed with ribs for anchoring slugs against vertical displacement.
8. A galley as described in claim 7, wherein the ribs formed on the partitions are semi-spherical in cross section and project from the opposed sides of the partitions and side walls and are adapted to fit into curved openings formed in opposite ends of the slugs to anchor the latter against vertical displacement.
9. A printing galley adapted to contain printing slugs of substantially less than standard type height, said galley comprising a bottom plate upon which the slugs are adapted to be supported at their lower edges, a plurality of parallel walls or partitions secured to the bottom plate and spaced apart to divide the galley into independent sections or compartments for different columns of slugs, and means associated with each of said compartments for anchoring the individual slugs against upward vertical displacement, said means being adapted to permit facewise movement of the slugs for insertion or removal.
10. A printing galley as specified in claim 9, characterized by the fact that the partitions therein recited are provided on their upper edges with printing surfaces or rules extending longitudinally thereof.
11. A galley as specified in claim 9 including a removable spacing block located at the foot of each slug column and adapted when removed to provide sufficient space for the facewise movement of the slugs to permit the removal of any selected one in the column by shifting it around to a diagonal position in the column.
12. A galley according to claim 9, in combination with a chase having a filler plate to

support the galley at the standard type height.

13. A printing galley adapted to contain printing slugs of substantially less than standard type height, said galley comprising a bottom plate upon which the slugs are adapted to be supported at their lower edges, a plurality of parallel walls or partitions secured to the bottom plate and spaced apart to divide the galley into independent sections or compartments for different columns of slugs, means associated with each of said compartments for anchoring the individual slugs against upward vertical displacement, said means being adapted to permit facewise movement of the slugs for insertion or removal, and means carried by the galley for locking up the different columns of slugs in printing position in the respective sections or compartments of the galley.

14. A printing galley adapted to contain printing slugs of substantially less than standard type height, said galley comprising a bottom plate upon which the slugs are adapted to be supported at their lower edges, and a pair of parallel walls secured to the bottom plate, said walls being provided on their opposing faces with ribs or beads extending longitudinally thereof and adapted to engage notches formed in the opposite ends of the slugs, whereby the slugs while capable of being shifted lengthwise of the galley are anchored against upward vertical displacement therein.

15. A printing galley adapted to contain printing slugs of substantially less than standard type height, said galley comprising a bottom plate upon which the slugs are adapted to be supported at their lower edges, a pair of parallel walls secured to the bottom plate, said walls being provided on their opposing faces with ribs or beads extending longitudinally thereof and adapted to engage in notches formed in the opposite ends of the slugs, whereby the slugs while capable of being shifted lengthwise of the galley are anchored against upward vertical displacement therein, and means carried by the galley for locking up the slugs in column formation in the galley.

16. A printing galley adapted to contain printing slugs of substantially less than standard type height, said galley comprising a bottom plate upon which the slugs are adapted to be supported at their lower edges, and a plurality of parallel walls or partitions spaced apart to divide the galley into independent sections or compartments for different columns of slugs, said walls being provided on their opposing faces with ribs or beads extending longitudinally thereof and adapted to engage in notches formed in the opposite ends of the slugs, whereby the slugs in any column while capable of being shifted

lengthwise of the galley are anchored against upward vertical displacement therein.

17. A combination as specified in claim 16 including a chase adapted to support the galley at the standard type-high level.

18. A printing galley adapted to contain printing slugs of substantially less than standard type height, said galley comprising a bottom plate upon which the slugs are adapted to be supported at their lower edges, a plurality of parallel walls or compartments spaced apart to divide the galley into independent sections or compartments for different columns of slugs, said walls being provided on their opposing faces with ribs or beads extending longitudinally thereof and adapted to engage in notches formed in the opposite ends of the slugs, whereby the slugs in any column while capable of being shifted lengthwise of the galley are anchored against upward vertical displacement therein, and means carried by the galley for locking up the different columns of slugs in printing position in the respective sections or compartments of the galley.

19. A method of assembling for printing, slugs of considerably less than type height, which consists in securing them in a rigid galley whose permanently attached floor is of insufficient thickness to support the slugs at type height above a given datum line, and securing said galley in a chase of considerably greater height than that of the galley within which also is fitted a filling piece of the thickness necessary to support the galley-supported slugs with their printing faces at type height relatively to the said datum line.

20. A galley for carrying out the method according to claim 19, presenting rectangularly disposed walls confining within them two or more columns of printing slugs and having means associated with the walls confining the sides of a column, for anchoring the individual slugs against vertical displacement, characterized by the fact that the wall or walls between adjacent columns are permanently attached to the galley floor.

21. A galley for carrying out the method according to claim 19, presenting rectangularly disposed walls confining within them two or more columns of printing slugs and having means associated with the walls confining the sides of a column, for anchoring the individual slugs against vertical displacement, characterized by the fact that the wall or walls between adjacent columns are permanently attached to the galley floor, in combination with a chase for receiving the galley, and a filler piece located within the chase beneath the galley to support the slugs at the standard type-high level.

In testimony whereof, this specification has been duly signed.

FRANK C. FROLANDER.
